WALTER MOORE PHILLIPS, OF PORTSMOUTH, OHIO.

ATTACHMENT FOR WIND INSTRUMENTS.

1,204,060.

Specification of Letters Patent.

Patented Nov. 7, 1916.

Application filed May 19, 1915. Serial No. 29,107.

To all whom it may concern:

Be it known that I, WALTER M. PHILLIPS, a citizen of the United States, and a resident of Portsmouth, in the county of Scioto and State of Ohio, have invented a new and Improved Attachment for Wind Instruments, of which the following is a full, clear, and exact description.

My invention has for its object to provide an attachment for cornets, trombones and similar musical instruments which will enable the performers to acquire the art of playing the instrument without undue pressure of the mouth piece against his lips. The attachment may also be used as a shock absorber for protecting the lips of the performer while marching.

Additional objects of the invention will appear in the following specification in which the preferred form of my invention is disclosed.

In the drawings similar reference characters refer to similar parts in all the views in which—

Figure 1 is a side elevation of the invention; Fig. 2 is a sectional view on the line 2—2 of Fig. 1; and Fig. 3 is a sectional view similar to that shown in Fig. 2, but with the mouth piece pressed inwardly to bring the openings in the telescoping tubes into communication with each other.

In playing cornets, trombones and similar musical instruments it is desirable that the mouth pieces be held close to the lips of the performer, but without pressure. This art, which is so important in order that the best results may be obtained has been learned by only very few performers for only when a beginner has one of the best teachers, or when he holds the mouth piece of the instrument to his lips properly during his early attempts, will he acquire the art which is necessary to perfect the performer.

My attachment, when used, teaches the performer how to hold the mouth piece to his lips and after he has learned this lesson, the attachment may be used by him as a shock absorber when playing his instrument while marching.

By referring to the drawings it will be seen that two tubes 5 and 6 are provided, these tubes telescoping with each other and being each provided with an orifice, the orifice in the tube 5 being indicated at 7 and the orifice in the tube 6 being indicated at 8. Normally, the tubes 5 and

6 are extended so that the orifices 7 and 8 do not communicate with each other; but, when the tube 6, with which is connected the mouth piece 9 is pressed inwardly, the orifice 8 will communicate with the orifice 7 in the manner indicated in Fig. 3 of the drawings. The tube 6 tapers at its outer end so that the mouth piece 9 may be fitted therein, and the outer end of the tube 5 tapers so that it may be secured in the tube 10 of a musical instrument.

Disposed around the telescoping tubes 5 and 6 there is a casing 11, this casing 11 having a head 12 which is secured to the tube 6 by any suitable means. Disposed around the tube 5 there is a disk 13, this disk 13 being provided with a threaded orifice 14 and a screw 15, the screw 15 being disposed in a longitudinal slot 20 in the casing 11 to prevent the rotation of the disk 13 relatively to the casing 11. The screw also meshes in the threaded orifice 14 and engages the tube 5 to prevent the rotation of the disk 13 relatively to the said tube. Disposed around the telescoping tubes 5 and 6 there is a spring 16 which, at its end 17 engages the head 12 of the casing 11 and at its end 18, engages the disk 13. This spring 16 serves to hold the tubes 5 and 6 yieldingly extended.

When the attachment is made use of, to teach a beginner how to hold the mouth piece to his lips, the screw 15 is turned out of engagement with the tube 5, then the tube 5 is rotated to a position where its orifice 7 will be in alinement with the orifice 8 in the tube 6. The screw 15 is then turned home and when the instrument is played, to which the attachment is secured, any undue pressure against the mouth piece 9, will move the tube 6 inwardly until the orifice 8 comes into communication with the orifice 7 when the air, passing into the mouth piece 9, will escape through the orifices 8 and 7 to the casing 11, which will make such a discord as will warn the player that he is using unnecessary pressure against the mouth piece. As the head 12 is secured to the tube 6 so that the casing 11 is prevented from rotating relatively to the said tube and as the tube 5 is prevented from rotating relatively to the casing 11 by the slot 20, the screw 15 and the disk 13, it will be seen that the tubes 5 and 6 will be held in the said position as long as desired and that

the orifices 7 and 8 will communicate with each other when the tube 6 is pressed inwardly. However, it will be understood that the attachment may not only be used for instructing players, but it also may be used as a shock absorber, when the instrument is to be played while marching; and when it is desired to make use of the attachment merely as a shock absorber, the screw 15 10 may be turned out of engagement with the tube 5 and the tube 5 may be rotated relatively to the casing 11 and the tube 6 so that the orifice 7 in the tube 5 will be at a position where the orifice 8 cannot communicate 15 with the orifice 7, when the tube 6 is pressed inwardly relatively to the tube 5. The screw 15 may then be turned home to secure the tube 5 in the said adjusted position. A band 20 is disposed around the casing 11 at the slot 20, and is adjustable longitudinally of the casing 11 so that the band 21 may be used to take up the slack when the tension 25 of the spring 16 is increased or decreased by the adjustment of the disk 13.

25 Having thus described my invention I claim as new and desire to secure by Letters Patent:

1. In an attachment for wind instruments, a mouthpiece, two telescopic parts to one of which the mouthpiece is secured, there being an opening in each part through which the interior of the inner part may communicate with the exterior of the outer part, and resilient means for holding the parts yieldingly in normal position, and with the openings spaced from each other.

2. In an attachment for wind instruments, two telescopic tubes having passages therethrough, one of the tubes having an open 40 end adapted to receive a mouthpiece, the other tube having an open end adapted to be attached to a wind instrument, there being openings in the sides of the tubes through which the interior of the inner tube 45 may communicate with the exterior of the outer tube when one of the tubes is pressed to a predetermined position relatively to the other, and resilient means for holding one of the tubes relatively to the other out of 50 the said position.

3. In a mouthpiece for wind instruments, two telescopic tubes, a casing secured to one of the tubes, the body of the casing being disposed around and spaced from the tubes, a disk secured to the other tube, and a spring disposed around the tubes and engaging the casing at one end and the disk at the other end.

4. In a mouthpiece for wind instruments, two telescoping tubes, there being an opening in a side of each of the tubes, a casing secured to one of the tubes, the body of the casing being spaced from the tubes, a disk secured to the other tube, and a spring disposed around the tubes and engaging the casing at one end and the disk at the other end, to hold the tubes extended with the openings out of communication with each other.

5. In an attachment for wind instruments, two telescopic tubes, a casing secured to one of the tubes, the body of the casing having a longitudinal slot and being spaced from the tubes, a disk rotatably mounted on the other tube, and means disposed in the slot 75 for securing the disk to the last-mentioned tube in adjusted position, there being an opening through the side of each of the tubes through which the interior of the inner tube may communicate with the exterior of the 80 outer tube when one of the tubes is moved to a predetermined position relatively to the other tube.

6. In an attachment of the class described, two telescoping tubes, a casing secured to one of the tubes, the body of the casing having a longitudinal slot and being spaced from the tubes, a disk adjustably secured to the other tube, a projection on the disk disposed for moving in the slot in the casing, 90 and a spring disposed around the tubes and engaging the casing at one end and the disk at the other end for the purpose specified.

7. In an attachment for wind instruments, two telescopic tubular parts, one open at its outer end for receiving a mouthpiece, resilient means for holding the parts yieldingly extended, there being an opening in the side of the inner tubular part and an opening in the side of the outer tubular part for 100 communicating with the first opening, so that when one of the parts is pressed abnormally relatively to the other against the resiliency of the said means, the openings in the parts will communicate with each other, 105 and air will pass therethrough to make a discord, thereby warning the student as set forth.

In testimony whereof I have signed my name to this specification in the presence of 110 the two subscribing witnesses.

WALTER MOORE PHILLIPS.
